Fig. 2

FIG. 1 is a top view of a manicure case embodying my design;

FIG. 2 is a rear view of the device;

FIG. 3 is a top view similar to FIG. 1 but with the cover removed, the broken line showings of the manicuring accessories being for illustrative purposes;

FIG. 4 is a rear view similar to FIG. 2 but with the cover removed;

FIG. 5 is a front view of the case with the cover removed; and

FIG. 6 is a bottom view of the case.

The dominant features of the design are shown in solid lines.

I claim:

The ornamental design for a manicure case, as shown and described.
